Primary Examiner — Elizabeth Albert(74) *Attorney, Agent, or Firm* — McGuireWoods, LLP(57) **CLAIM**

I claim the ornamental design for a white board, as shown and described.

DESCRIPTION

FIG. 1 is a perspective view of a while board showing my new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is another perspective view of FIG. 1;

FIG. 9 is a another perspective view of FIG. 1 with the cover pulled away;

FIG. 10 is another perspective view of FIG. 1; and,

FIG. 11 is another perspective view of FIG. 1.

The subject matter shown in dashed lines is included to show features that form no part of the claimed design.

1 Claim, 9 Drawing Sheets(56)
